TRANSFER DEVICE FOR KNITTING MACHINES

Filed Oct. 25, 1929

BY *Max D. Ordmann*
ATTORNEYS.

UNITED STATES PATENT OFFICE

FRED DOST, OF FREEPORT, NEW YORK, ASSIGNOR TO ROBERT REINER INC., OF WEEHAWKEN, NEW JERSEY

TRANSFER DEVICE FOR KNITTING MACHINES

Application filed October 25, 1929. Serial No. 402,355.

In stocking knitting machines as is well known, it is customary to have a plurality of needle bars arranged in a bank and to knit the corresponding number of stockings simultaneously. In case, however, that the thread fed to one of said stocking webs breaks during the knitting process, the said web strips itself from its needle bar and it is necessary to stop the entire machine and remount the web on said needle bar. In view of the fact that there are a great number of needles to each bar and also that each stitch of the web must be mounted on one of said needles, considerable time is consumed and as a result the speed of production is greatly curtailed.

One object of the present invention is to provide means which may be employed in conjunction with existing machines whereby curtailed production due to the above indicated cause will be eliminated.

A further object is to provide a device which may readily be attached directly to existing machines.

Another object is to provide a device which is simply constructed and which may be manufactured at low cost.

Still another object is to provide a device which may be adjustable to suit the convenience of the particular operator.

With the above and other objects in view, my invention consists in the novel construction, combination and arrangement of elements as will hereinafter be more fully described, shown in the accompanying drawings and claimed in the appended claims.

In the drawings which form part of this specification and in which similar reference characters denote corresponding parts:

Fig. 1 is a side elevation of my device;

Fig. 2 is a top plan view thereof;

Fig. 3 is a sectional detail along line 3—3 of Fig. 1 seen in the direction of the arrows;

Fig. 4 is a section along line 4—4 of Fig. 2 also seen in the direction of the arrows; and

Fig. 5 is a view of a detail of my device.

In the drawings 10 denotes a base to which is removably attached an upright 11. There are two such bases and uprights, one for each end of my device. Adjustably mounted on each of said uprights, as by means of a set

screw 12 is a supporting frame 13. Projecting from the front edges of said frames are a plurality of fingers 13' which may be integrally formed therewith and which are for a purpose hereinafter specified. A joining member or cross bar 14 which may be suitably fixed in openings 13² in said frame as by means of set screws 15 serves to space said frames from each other. Provided on the upper ends of said frames 13 may be pedestals 16 to which may be mounted the supports 17 on which are mounted the operating elements of my device. The said supports may be rigidly joined as by means of a cross rod or bar 18 or the like. Mounted across the top of said supports 17 is a needle bed 19. On said bed lies a strip 20 provided with a plurality of parallelly arranged notches 20' in which needles 21 are adapted to lie. Mounted over said strip and adapted to clamp said needles in place are a plurality of clamping blocks 22 which may be bolted to the needle bed 19 by suitable bolts 22'. By providing a plurality of said blocks, if one of the needles 21 breaks it is merely necessary to remove the clamping block under which the said needle lies without disturbing the greater part of the clamped needles. Each of the needles 21 project forwardly from the needle bed towards the front of the supports 17, and is provided with a longitudinal groove 21' for a purpose hereinafter specified.

Pivottally mounted between the supports 17 as for instance at 23 is a U-shaped support 24 across the upper ends which is mounted a rake-like member 25 the tines 25' of which are adapted to project upwardly between the parallelly mounted needles 21.

Normally the support 24 is adapted to rest in the position shown in Fig. 4 so that the rake-like member 25 abuts the front edge of the needle bed 19. In order to rotate said support forwardly and cause said tines 25 to move forwardly towards the points of said needles 21 an operating handle 26 may be connected to said rake-like member 25 as at 27 and curved downwardly and around to the rear of said needle bed 19. By pulling said handle forwardly the tines are thereby also

caused to move forwardly. An adjustable stop screw 28 which is adapted to come in contact with the rear edge of said needle bed 19 may be mounted in the handle 26 for limiting the forward movement of the tines 25'.

Pivottally mounted to each of the supports 17 as at 29' is a needle bar support 29 which has a slot 29² near the front edge of the upper face thereof. A cross bar 30 suitably fastened to each of the supports 29 joins the same together.

The needle bar 31 which is used with the transferring device has a plurality of parallel laterally extending needles 31' which are suitably fastened to said bar. Each of the said needles 31' is provided with a longitudinal groove 31² in the usual manner.

The said slots 29² in the supports 29 are dimensioned to receive therein the free ends of said needle bar 31 whereby the needles 31' will register with needles 21, there being a corresponding one of the latter needles for each of the former ones, and the points of said needles 31' are adapted to lie in the slots 21' of said needles 21. To permit rapid mounting of said needle bar 31 in position whereby the registration of the needles as above described occurs, I may provide in one of the slots 29² an adjustable stop 32 which may be so positioned in said slot whereby if an end 31² of the needle bar 31 abuts the same, the said needles 31' will register with needles 21.

In operation my device is employed as follows:—

When the thread breaks on one of the webs being knitted on the knitting machine, the web strips itself from the needles of said machine as previously described. Instead of stopping the machine however, the said web is removed and the stitches thereof mounted on the needles 21 of my transferring device. Then a needle bar 31 which for instance may be carried on the racks formed by the projections 13' on my device, is placed in position in slots 29' and the handle 26 is pulled forwardly causing the tines 25' to push the stitches from needles 21 onto needles 31'. Then the knitting machine is momentarily stopped and the stripped needles of the machine laid out and the needles 31' of needle bar 31 caused to register with the said machine needles and the stitches of said web transferred to the latter. Then the machine is started again.

Instead therefore of wasting a great deal of time remounting the stitches on the needles in the machine it is possible to remount the same to said needles with my auxiliary device.

The supports 10 of my device may be shaped to fit onto the knitting machine bed so that my device may be conveniently located for the operator and likewise by means 65 for instance of set screws 10' and 12' the

height of my device may be varied to suit the particular operator.

My device may be modified in many ways without departing from the spirit of my invention and I do not wish to be limited to 70 the details shown and described.

What I claim is:—

1. A device for knitting machines, comprising two bases having vertically extending uprights, a supporting frame mounted to each upright each having fingers projecting from the front edges thereof, a joining member extending between said frames and spacing the latter from each other, supports mounted on each of said frames, a joining member extending between said supports, a needle bed mounted across the top of said supports, means on said bed for parallelly mounting a plurality of needles, the said needles when mounted being adapted to project forwardly from said needle bed towards the front of said supports, a support pivotally mounted between said first named supports having a rake-like member mounted across its upper end, the tines of said member projecting upwardly between said parallelly mounted needles, a needle bar support pivotally mounted to said first named supports, means on said needle bar support for facilitating rapid mounting of said needle bar in position whereby the needles thereon register with those on said needle bed, and means for moving said pivotally mounted rake-like member whereby the tines thereof will transfer stitches held on said needle bed needles to said needle bar needles. 90

2. A device for knitting machines comprising a base, a vertically adjustable support mounted on said base, a needle bed mounted on said support, means for parallelly mounting in spaced relationship a plurality of needles on said bed, a frame pivotally mounted to said support on which a needle bar may be removably laid, means on said frame for obtaining registry of said needle bar needles with the needles on said bed, a rake-like member pivotally mounted to said support, the tines of said member extending upwardly into the spaces between needles on said bed and means for moving said pivotally supported rake-like member whereby the tines thereof may transfer stitches from said needle bed needles to said needle bar needles. 105

3. A device for knitting machines comprising spaced bases each having vertically extending uprights, a supporting frame mounted on each upright, supports mounted on each of said frames, a needle bed mounted across the top of said supports, means on said bed for parallelly mounting a plurality of needles, the said needles when so mounted, projecting forwardly towards the front of said supports, a rake-like member extending between and pivotally mounted to said sup- 125

ports, the tines of said member extending respectively between said parallelly mounted needles, a needle bar support pivotally mounted to said supports, means on said needle bar support for readily securing registry of said needle bar needles with said needle bed needles and means for moving said pivotally mounted rake-like member whereby the tines thereof will transfer stitches held on 10 said needle bed needles to said needle bar needles.

In testimony whereof I affix my signature.
FRED DOST.
